VENETIAN BLIND STRUCTURE

Charles S. Evans, Atherton, Calif., assignor to Calnetian Blinds, Incorporated, Oakland, Calif., a corporation of California

Continuation of application Serial No. 784,012, November 4, 1947. This application July 14, 1953, Serial No. 367,854

5 Claims. (Cl. 160—178)

This application is a continuation of my copending application Serial Number 784,012, filed November 4, 1947, now abandoned.

My invention relates to Venetian blinds, and particularly to means for securing the blind slats in the ladder tape.

The principal object of the invention is the provision of improved means for detachably connecting the rung tapes to the slats.

The invention possesses other objects, some of which with the foregoing will be set forth at length in the following description wherein are explained those forms of the invention which have been selected for illustration in the drawings accompanying and forming a part of this specification. In said drawings, illustrative forms of the invention are shown, but it is to be understood that it is not limited to those forms, since the invention as set forth in the claims may be embodied in a plurality of other forms.

Referring to the drawings:

Figure 1 is a horizontal sectional view of a portion of a Venetian blind embodying my invention. The view is taken through one of the ladder tapes immediately above a pair of rung tapes and the snap slide disposed thereon. A slat resting on the next lower pair of rung tapes, and broken away on each side of the ladder tape is shown.

Figure 2 is a vertical sectional view of a portion of the blind structure, showing a slat engaged on a snap slide which in turn rests on a pair of rung tapes. The plane of section is just inside the front web of the ladder tape.

Figures 3, 4 and 5 are respectively side elevation, top and bottom views of the snap slide shown in Figures 1 and 2.

Figure 6 is a plan view of a portion of slat, showing the socket member of the snap fastener, the stud member of which is on the slide.

Figures 7, 8 and 9 show another embodiment of my invention, Figure 7 being a side elevation of a piece of slat in which the stud of the snap fastener is fixed. Figures 8 and 9 are respectively plan and vertical section of a snap slide including a socket. The plane of section of Figure 9 is indicated by the line 9—9 of Figure 8.

Figures 10, 11 and 12 are respectively plan, elevation and bottom views of another embodiment of my invention; and

Figures 13, 14 and 15 are respectively plan, elevation and bottom views of still another embodiment.

The scale of Figures 1 and 6 is approximately full size, but each of the other figures is drawn to a scale of approximately 1½ to 1.

The Venetian blind art is an old one. Venetian blinds were in use in the United States before the Revolution, but in spite of many advantages, the housewife has always found them difficult to clean, because getting out the slats so that they could be sponged off and wiped was a job only slightly less arduous than taking the shingles off the roof. For a like reason any change of or repair

2

to the slats usually required a skilled workman and disproportionate expense.

The problem of providing a Venetian blind with readily removable slats has long been an attractive one; and inventors have approached it in many ingenious ways, but never before have all the elements of the problem been harmonized to produce a structure which the public would accept. These elements include cost of manufacture, mechanical structure, method of operation, and appearance. No Venetian blind structure can secure wide public acceptance which is not sold at a price the careful purchaser will pay, or which varies too widely from the familiar forms, or which embodies strange or questionable mechanisms or which is not operable by simple means in a way immediately apparent to the non-mechanical mind.

It is believed that the present invention combines to an unusual degree the qualities required for a reasonably good compliance with the demands imposed by the above named elements. A Venetian blind embodying this invention does not differ in general appearance from the older and familiar blinds. When organized on the same basis, the cost of manufacture need be no greater, and may be less than the older blind. The structure is of the simplest and its use and operation are immediately apparent.

Venetian blind ladder tape is mainly of two broad types, woven or warp thread rungs arranged in staggered formation between vertical webs, and double or twin-cord rungs evenly spaced on the webs. The staggered rung tapes while low in production costs distribute stresses unevenly on the webs, and contribute to a tendency to uneven folding of the webs when the blind is raised. The twin-cord rungs impart a degree of undesirable stiffness to the webs, and the tape is more expensive to produce.

The ladder tape which I prefer to use, provides twin rung tapes of warp thread or string type, or of woven type interwoven at their ends in the vertical webs. This tape may be produced with looms and by methods analogous to those currently in use to produce the staggered single rung tape; and it is characterized by the fact that the rung tapes of each pair are spaced the same distance apart throughout the length of the ladder tape; and are also evenly spaced on each side of a vertical plane through the longitudinal center line of each web.

Referring first to Figure 1, the two vertical webs 2 and 3 of the ladder tape are connected at equal intervals vertically by the twin rung tapes 4 and 5. The rung tapes are of the fully woven type or string type, and are woven into the vertical webs during the weaving of the latter.

A slat 7, preferably of thin metal is supported on each pair of rung tapes, it being understood of course that a similar ladder tape assembly is provided at each side of the blind so that the slats are supported adjacent each end. With blinds having long slats, one or more intermediate ladder tapes are used.

The distance between the vertical webs 2 and 3 is greater than the width of the slat to give ample space for the lifting cord 8 which extends along the inside of one of the webs between it and the slats. Where but two lifting cords are used, they are placed on opposite sides of the slats, one at each end of the slats. Two lifting cords at each end of the slats may be used, and when this is done, a lighter cord is preferred.

Means are provided for releasably securing each slat to at least one pair of its supporting rung tapes, so that accidental release and longitudinal movement of the slat is prevented, but free lateral movement of the slat is insured in automatic adjustment of its position during operation of the blind.

But one connection between a slat and the run tapes is needed to retain the slat in perfect alignment; and this is provided by the slide 9, Figure 1, which encloses both rungs of the associated pair as shown. It is preferable to arrange the slides under alternate slats on one end of the blind and under the intervening slats at the other end.

The slide 9 is comprised of two main parts, the fastener element which engages resiliently and releasably in the complementary fastener element of the slat; and the main body portion, which furnishes a free slideway for and encloses the twin rung tapes which support it and the connected slat.

Because it is very desirable to have the slats even and smooth to facilitate taking them out of the ladder tapes and putting them back; as well as to facilitate cleaning them while disassembled, the socket member of the fastener combination is preferably placed in the slat; and in this case is merely a small round hole 12 punched in the slat, preferably when it is cut to length. While one such hole is all that is needed, it is preferred to punch a hole at each end of the slat so that it is reversible as well as removable. The companion member of the fastener comprises a resilient stud carried on the main body of the slide. Figures 3, 4 and 5 show side, top and bottom views respectively of the slide, the dotted lines of Figure 3 indicating the position of the lower arm when the slide is closed about the rung tapes as in Figure 2.

The slide is formed in suitable dies from a thin strip of hard brass, and comprises an upper arm 13 and lower arm 14 connected at one end by the bend 16. The free ends of the arms are provided with curved, interfitting and complementary parts 17 and 18 and the proportions and shapes and tensions are such that while the slide comes from the dies with the lower arm open as shown in Figure 3, pressure between the thumb and finger closes the lower arm, seating the curved end 18 within the curved end 17 of the upper arm, in which position the parts form a flat closed loop and are held resiliently together so tightly that they are not readily released except with the aid of a metal pry.

It will be noted that the lower arm 14 in the open position is slightly curved away from the upper arm. The resilience of the metal, the proportions of the bend 16, the curvature of the arm, the width, length and position of the hole 21 in the lower arm, and the curvature and proportions of the arm ends 17 and 18, are factors which must be carefully balanced to secure a slide which may be easily closed over the rungs and will retain its closed position against any accidental force, but which is readily pried open without injury if opening is necessary.

The upper arm 13 is formed with a wide depressed or reentrant portion 22 extending laterally across the central part of the arm. From the central portion of the depressed part rises the fastener element or stud 23, adapted to engage the socket 12 in the slat. This stud is a well known article of commerce commonly known as the "bird cage" type; and is closely similar to the stud of a glove fastener. The stud is secured to the slide in the usual way by passing the shank of the eyelet 24, through a hole in the slide and into the base of the stud where it locks the parts securely together. Because of its structure the "bird cage" stud possesses considerable resilience and therefore only a simple round hole is required in the metal slat as the complementary fastener element. This has great significance, because it leaves the slat clear and smooth so that it is handled and washed or wiped more readily and without danger of injury to the hands or catching the cleaning cloth.

The reason for having a depressed portion from which to raise the stud part, is to have a sufficient length of stud for flexibility without making over-all height too great.

In spite of the obvious advantages of a smooth slat, it is sometimes necessary, as where wood slats are used, to reverse the fastener elements, putting the stud on the slat and the socket in the slide. Figures 7, 8 and 9 illus-

trate this arrangement. A solid stud 27 is fixed in the slat 28, and is adapted to engage the socket 29 in the slide. As best shown in Figure 9, the socket is formed as a dimple, the inturned flange 31 of which is slotted at 32 on opposite sides to increase resilience, all of which must be in the socket, with a solid stud. The body of the slide and the interlocking arms are the same as explained in connection with Figure 3.

In Figures 10, 11 and 12 a slide is shown which differs from that of Figure 3 mainly in the kind of interlock between the arm ends. The flat downwardly turned end 35 of the upper arm is formed with a slot 36, in which engages the outwardly turned prong 37 on the upwardly extending end 38 of the lower arm. The parts are so proportioned and arranged that when the arms are pressed together the prong engages the inside of the upper arm end, and slides along it, flexing the lower arm, until it snaps into the slot from which it can be disengaged only by applying a distorting force to the lower arm. An aperture 39 divides most of the lower arm into two parts, and this aperture is carried past the bend 41 and into the upper arm as shown. The reason for this structure is to give greater resilience and flexibility to the lower arm. This slide is used where it is desired to make permanent the connection with the rung tapes.

In Figures 13, 14 and 15 are shown a type of slide particularly useful where it is desirable to reduce the over-all thickness of the slide to the minimum. This type has a two-part body which must be assembled for a complete structure.

A "bird-cage" type of stud 43 is fixed in a lower plate 44, preferably in an upwardly offset portion 46 as shown. Each end 47 of the plate is curved upwardly complementary to the downwardly curved ends 48 of the upper plate 49, the proportions being such that the two may be pressed together, the lower plate then being resiliently held within the upper plate. The upper plate is formed with a central aperture 51 through which the stud extends without touching to engage in the slat hole 12, Figure 6. This slide is very thin and lies snugly against the slat with which it is engaged.

In all of the slides it is desirable to have their inside length, a small amount less than the over-all width of the supporting twin rung tapes, so that the outer edges or strings of the tapes are drawn together a trifle out of parallelism as shown in Figure 1. This helps materially in maintaining a desired longitudinal alignment of the ends of the assembled slats, since it constitutes an angular guy from each edge of each vertical web to the stud.

An important function of the slide is to move easily along the rungs of the ladder tape when the slats are tipped, so that the slats adjust themselves in parallelism as they are moved to control the light. The slat is always narrower than the rung is long, the difference being the maximum amount of adjusting movement when the slats are tipped. Turning of the slide so as to cramp it into the side of the soft rung would immobilize the slide and connected slat, and give an uneven alignment and objectionable appearance to the slats. To prevent such turning, the width of the slide along the rung must be a considerable part of the length of the slide across the rung, so that any turning moment exerted on the slide is resisted by a sufficiently broad bearing between slide and rung.

I claim:

1. In a Venetian blind in which slats are supported by a ladder tape including a rung structure, means for slidably and demountably connecting each slat with the rung structure of the ladder tape comprising, a resilient strip having a bend adjacent its mid. point to provide two plates normally resiliently divergent therefrom, interlocking means on the free ends of the plates to lock them together in spaced parallelism and forming a closed loop when the plates are pressed together about the rung structure, said plates being held biased in said spaced parallelism by said interlocking means, and a releasable resilient

fastener element disposed on one of the plates to releasably engage a complementary fastener element on the adjacent slat.

2. In a Venetian blind in which slats are supported by a ladder tape including a rung structure, means for slidably and demountably connecting each slat with the rung structure of the ladder tape comprising, a resilient strip having a bend adjacent its mid point to provide two plates normally resiliently divergent therefrom, interlocking means on the free ends of the plates to lock them together in spaced parallelism and forming a closed loop when the plates are pressed together about the rung structure, said plates being held biased in said spaced parallelism by said interlocking means, one of said plates having a portion depressed toward the other plate, and a resilient stud comprising a releasable fastener element disposed on the depressed portion to releasably engage a complementary fastener element on the slat.

3. In a Venetian blind in which slats are supported by a ladder tape including a rung structure, means for slidably and demountably connecting each slat with the rung structure of the ladder tape comprising, a resilient strip having a bend adjacent its mid point to provide two plates normally resiliently divergent therefrom, interlocking means on the free ends of the plates to lock them together in spaced parallelism and forming a closed loop when the plates are pressed together about the rung structure, said plates being held biased in said spaced parallelism by said interlocking means, one of said plates having an aperture therethrough to adjust its flexing resilience, the other of said plates having a portion depressed toward the apertured plate, and a resilient stud comprising a releasable fastener element disposed on the depressed portion to releasably engage a complementary fastener element on the slat.

4. In a Venetian blind in which slats are supported by a ladder tape including a rung structure, means for slidably and demountably connecting each slat with the rung structure of the ladder tape comprising, spaced plates normally spread apart and having resiliently interlocking means thereon to lock them in fixed spaced relation and comprising a closed loop when the plates are pressed together about the rung structure, said plates being biased away from each other at an angle when said interlocking means thereon is in a released condition, and a releasable resilient fastener element disposed on one of the plates of the loop for engaging a complementary releasable fastener element on the adjacent slat.

5. In a Venetian blind having ladder tape with rungs arranged in pairs spaced apart horizontally, means for demountably connecting the slat to pairs of rungs comprising, spaced plates having resiliently interlocking means thereon to lock them in fixed spaced relation and comprising a closed loop for loosely enclosing a pair of rungs, the size of the loop relative to the horizontal spacing of the pairs of rungs being such as to draw the rungs of the pair slightly together, and a releasable snap fastener element on one of the plates of the loop to releasably engage a complementary snap fastener element on the adjacent slat.
